UNITED STATES PATENT OFFICE.

ANDREW J. BERNARD, OF NEW ORLEANS, LOUISIANA, ASSIGNOR OF FOUR-TENTHS
TO ERNEST M. LOEB, OF NEW ORLEANS, LOUISIANA.

FILM-MENDER.

1,173,142.

Specification of Letters Patent. Patented Feb. 22, 1916.

Application filed June 26, 1915. Serial No. 36,498.

To all whom it may concern:

Be it known that I, ANDREW J. BERNARD, a citizen of the United States, residing at New Orleans, in the parish of Orleans and 5 State of Louisiana, have invented certain new and useful Improvements in Film-Menders; and I do hereby declare the following to be a full, clear, and exact description of the invention, such as will enable 10 others skilled in the art to which it appertains to make and use the same.

The present invention relates to improvements in film menders, and consists more particularly in a device for mending the 15 marginal edges of motion picture films containing the feed perforations. Incident to rough handling and usage in running films through the projecting apparatus and in rewinding the same for subsequent use, such 20 films constantly sustain breakages, especially along the marginal edges which contain the series of perforations engaged with the drive sprockets.

It is the purpose of this invention to provide 25 a device for securing along the broken marginal edges of films, tapes or ribbons provided with equidistantly spaced perforations corresponding in configuration to the perforations in the edges of the film.

30 A further object of the present invention resides in providing an improved film mender of the above character which will be equipped with a device for carrying a perforated ribbon or tape movable to a position above either of the marginal edges of the film, which is arranged upon a clamping device for holding the tape after the same has been applied and cemented.

With these and other objects in view the 40 invention consists in the novel details of construction and combinations of parts more fully hereinafter disclosed and particularly pointed out in the claims.

In the accompanying drawings forming 45 a part of this application, and in which similar reference symbols indicate corresponding parts in the several views: Figure 1 is a top plan view of an improved film mender constructed in accordance with the 50 present invention and illustrating a film as applied thereon. Fig. 2 is a side elevational view of the same; and Fig. 3 is a cross sectional view of the improved device with parts shown in elevation and with the ribbon 55 attachment.

Referring more particularly to the drawings, wherein one embodiment of the present invention is illustrated, 1 designates a table or other supporting structure, upon which is mounted the bed or base 2 of the 60 improved film mender, the same being provided with lugs 3 perforated for the passage of the screws 4 whereby the attachment is effected.

Along the rear edge of the base 2 are 65 hinged, as indicated at 5, a series of clamps 6 disposed adjacent and adapted to be independently movable about said hinge connections 5. The clamps 6 are arranged to be lowered upon the base 2, in which position they secure and confine the film 7, and where they are held by pivoted catches 8, provided each with a cam extension 9 for riding over the free upper edge of the respective clamps and pressing the latter into 75 close engagement with said base.

The base 2 is provided with separate series of teeth 10 and 11, equidistantly spaced and corresponding to the sprocket holes on the film 7. In the several clamps 80 6 are series of sockets 12 and 13, provided to receive the respective series of teeth 10 and 11 when said clamps are revolved to position in engagement with the base 2 to secure the film during the mending operation. The base 2 and clamps 6 are provided with complementary channels 14 and 15, extending opposite the central portion of the film, upon which are contained the picture series whereby the parts of the device 85 will not come in contact with said portion of the film, which would otherwise be likely to scratch or erase the pictures. 90

Referring now to Fig. 3, the supporting structure 1 is shown formed with a groove 95 15', in which is located bearings 16 for receiving a slidable rod 17 forming one horizontal member of a U-shaped holder 18, the other member 19 of which is arranged 100 to extend above the clamping device, and is constructed to receive a reel on which is wound a ribbon or tape 20 provided with equidistantly spaced perforations 21, corresponding in configuration to the sprocket holes in the film 7. By grasping the holder 105 18 the rod 17 may be moved to the full or dotted line position accordingly as it is desired to bring the ribbon roll 20 above the right or left side of the film 7, in which position the ribbon can readily be drawn down 110

and a suitable length cut therefrom for mending the broken edge of the film.

The operation of mending a film may be proceeded with on the above described device in the following manner:—The injured sprocket holes of the film 7 are cut off and the new ribbon or sprocket holes 20 are glued or cemented on same place as shown in Fig. 1, but it is preferable to cut the old injured edges off the film as economically as possible, so as to give more place on which to glue the new ribbon 20. Practice has shown that sometimes it is even preferable just to glue a new ribbon of sprocket holes on the old ones without cutting the broken edges off the film.

The injured film 7 is preferably cut away as indicated at 22 in Fig. 1, to remove the damaged edge of the same, and the film 20 subsequently applied on the base 2 with the sprocket holes thereof engaging with the series of teeth 10 and 11. In this position, it will be seen that the central portion of the film overlies the channel 14 in the base 2, and will not be scratched or injured by pressure or contact with the parts of the device. The holder 18, if the device is equipped with such, is now grasped and moved to bring the reel 20 above the cut-away portion 22 of the film 7, and the ribbon drawn down and a proper strip measured out over the length of the damaged portion. The strip is thereupon cut and applied with an adhesive to the adjacent sides 35 of the cut-away portion 22 of the film 7, care being taken to adjust the sprocket holes 21 in the ribbon 20 to agree with the position of the perforations in said film. Such of the clamps 6 as may be required, are 40 then brought down into engagement with the film and are secured by the pivoted catches 8. After sufficient length of time the catches 8 are removed and the clamps 6 withdrawn, when it will be found that the 45 ribbon is permanently applied to the film 7 and forms an unbroken series of sprocket holes. The film is now in readiness for subsequent operation.

It is obvious that those skilled in the art 50 may vary the details of construction and arrangements of parts without departing from the spirit of my invention, and therefore I do not wish to be limited to such features except as may be required by the claims.

55 I claim:

1. In an improved film mender of the character described, the combination with a supporting structure, of a base removably secured thereon and traversed by a longitudinal central channel, series of equidistantly spaced pins on both sides of said channel for receiving the perforations in the film margins, a series of independently

hinged clamps disposed contiguous and arranged to swing down to engage the base and bind the film and ribbon together during the mending operation, said clamps being provided with sockets for receiving said pins and with registering recesses adapted to aline with the channel in said base when the clamps are moved to engage the same, and catches pivoted to said base and provided with cam heads for engaging the free ends of said clamps and binding the same in tight engagement with the base, substantially as described. 65 70 75

2. In a film mender, the combination of a base constructed to receive the film, means for clamping said film during the mending 80 operation, and a ribbon holder slidably connected with said mender for bringing the ribbon over either marginal edge of said film, substantially as described.

3. A film mender including a base for receiving the film, clamp means associated with said base for securing the film during the mending operation, bearings associated with said base, a holder including a member 85 90 95 slidable through said bearings, said holder being adapted to support a perforated ribbon mounted on the same and movable thereby to bring the ribbon over either marginal edge of the film as the same lies on said base, substantially as described.

4. In a film mender, the combination of a base adapted to receive the film, clamp means associated with said base for binding the film during the mending operation, bearings associated with said base, a U-shaped 100 105 holder having a lower horizontal member slidably mounted through said bearings and an upper horizontal member extending above the base and clamping means, said upper member adapted to support a perforated ribbon roll movable above either marginal edge of the film on said base, substantially as described.

5. In a film mender, the combination of a supporting structure having a groove therein, a base mounted on said supporting structure and provided with a longitudinal channel, a series of teeth on said base to either side of said channel, a series of clamps hinged to swing independently on 110 115 120 said base and provided with channels and sockets for receiving said teeth, means for securing said clamps in engagement with said base, a ribbon holder slidable in the groove in said supporting structure, and having a perforated ribbon roll mounted thereon and arranged to be lifted from above one margin of the film on said base to a position above the other margin, substantially as described. 125

In testimony whereof, I affix my signature.
ANDREW J. BERNARD.
